UNITED STATES PATENT OFFICE.

GEORGE HENRY NUSSEY AND WILLIAM BRADSHAW LEACHMAN, OF LEEDS,
ENGLAND.

MACHINE FOR TENTERING, PRESSING, AND FINISHING WOOLEN OR OTHER FABRICS.

SPECIFICATION forming part of Letters Patent No. 416,641, dated December 3, 1889.

Application filed June 24, 1884. Serial No. 135,895. (No model.) Patented in England November 20, 1880, No. 4,815, and March 17, 1885, No. 3,450; in France May 20, 1881, No. 142,939; in Belgium May 23, 1881, No. 54,712, and in Austria-Hungary September 6, 1881, No. 40,569.

To all whom it may concern:

Be it known that we, GEORGE HENRY NUSSEY and WILLIAM BRADSHAW LEACHMAN, subjects of the Queen of Great Britain, both residing at Leeds, England, have invented new and useful Improvements in Machines for Tentering, Pressing, and Finishing Woolen or other Woven or Felted Fabrics, (for which we have obtained Letters Patent in Great Britain, dated November 20, 1880, No. 4,815, and March 17, 1885, No. 3,450; France, dated May 20, 1881, No. 142,939; Belgium, dated May 23, 1881, No. 54,712; Austria-Hungary, dated September 6, 1881, No. 40,569,) of which the following is a specification, reference being had to the accompanying drawings.

Our invention relates to machines for tentering, pressing, and finishing woolen or other woven or felted fabrics.

Our said invention is partly designed to improve the construction of the machine described in the specification of English Letters Patent, dated November 20, 1880, No. 4,815.

It also comprises various improvements whereby we provide a machine which will while tentering and pressing cloth or similar material effect the finishing thereof, as hereinafter set forth.

In our improved machine the cloth or other material while held by the list or selvage on each side and while being tentered is pressed between hot plates, so as to remove from it all creases or similar marks caused by dyeing and washing the material, and to finish it, as hereinafter described. In finishing it is necessary that the cloth or other material should be twice crabbed—that is to say, it must be wound upon a crabbing-roller or perforated copper cylinder closed at one end, and must then be treated by blowing steam through the said roller or cylinder and through the cloth or other material. The cloth or other material is usually wound on the said roller first from one end and then from the other end, because the part next the cylinder receives more finish than the part at or near the exterior by reason of the heat of the said cylinder, the steam having a tendency to con-

dense toward the exterior. This treatment 50 renders woolen fabrics rather tender, as they have to remain on the crabbing-rollers for a considerable time; but by our invention we obviate the necessity for this treatment, as the cloth is finished by pressure between the 55 hot plates on its passage through the machine, so that every yard or so of the cloth is pressed and finished separately. If much luster is required, we increase the heat of the plates, so as to fasten the face of the material. We 60 thus dispense with the boiling or blowing of the material, as usually practiced.

Our improved machine is illustrated in the accompanying drawings, in which—

Figure 1 is a plan, and Fig. 2 a side elevation, of the said machine. Fig. 3 is an end elevation of the same, partly in vertical section, on the line z z , Fig. 2. Fig. 3^a is an end elevation, drawn to an enlarged scale, showing details of construction. Fig. 3^b is a side 70 elevation showing details of construction. Fig. 4 is a plan; Fig. 5, a vertical section, and Fig. 6 an edge view, showing details of construction. Fig. 7 is a transverse section, and Fig. 8 a vertical longitudinal section, showing 75 parts of the said machine. Fig. 9 is a side elevation of a receiver, hereinafter described, for heating air. Fig. 10 is a transverse section of part of the said receiver.

a is a driving-pulley, which imparts motion 80 to the shaft a' . This shaft is provided with an endless screw or worm a^2 , which gears with a worm-wheel b^* , fixed on the shaft b' . The said shaft also has fixed thereon the cam b , which operates the valve of a steam-cylinder 85 c by means of the lever d . The pressure in the cylinder c is utilized directly for actuating the pressing-plates, as hereinafter described. a^3 is a loose pulley, which is fitted to rotate upon the shaft a' .

The mechanism for driving the chains and drawing the cloth through the machine is constructed as follows—that is to say: e is a driving-pulley, which is fitted to rotate upon the shaft e^* . e' is a conical piece keyed upon 95 the shaft e^* , but free to slide thereon and fitting into the pulley e , so as to form therewith a friction-clutch. The piece e' is fast to

a pinion f , Fig. 1, which is geared with a toothed wheel f' , fixed upon a shaft f^2 , on which is also fixed a bevel-pinion f^3 , geared with a bevel-pinion f^4 , fixed on a vertical shaft f^5 . On the lower end of the shaft f^5 is fixed a bevel-pinion f^6 , which is geared with a bevel-pinion f^7 , fixed on the shaft f^8 . A bevel-pinion f^9 is also fixed on the shaft f^8 , and is geared with a bevel-wheel f^{10} , fixed on the shaft f^{11} . The shaft f^{11} is connected with the shaft f^{12} at the other end of the machine by means of the toothed wheels f^{13} , f^{14} and the intermediate wheel f^{15} . Chain-wheels CC' are fixed on these shafts for driving the chain B $B' B^2 B^3$.

g is a forked lever for putting the said friction-clutch in and out of gear. This lever is pivoted at g^* , and is provided with an adjustable piece g' , having an inclined face g^2 . h is a bracket attached to the cross-head i , which is formed or fixed on the rod c' of the piston that works in the cylinder c . This bracket is provided with an anti-friction roller h' , and is arranged to act like a tappet and operate the lever g in each upstroke of the cross-head i , so as to throw the friction-clutch out of gear and thus arrest the passage of the material through the machine while it is being pressed. A weight g^3 is suspended from the lower end of the lever g by means of a chain g^4 passing over a pulley g^5 . The weight g^3 is fitted to slide up and down upon a guide-rod g^6 . A spring g^7 is attached to the frame of the machine and presses outward against the lower end of the lever g , so that when the weight g^3 is raised by hand, as hereinafter described, the said spring will operate the said lever and throw the clutch $e e'$ out of gear.

E is a lever or arm which is fixed upon a rock-shaft e^2 , carried in bearings in brackets E^* , secured to the base-plate of the machine. The rock-shaft e^2 also has fixed thereon a forked arm E' for shifting the belt from the fast pulley a to the loose pulley a^3 , and vice versa, and an arm E^2 , which is connected by a rod E^3 with the bent lever F . The horizontal arm of the lever F extends beneath a flange or nut g^8 on a rod g^9 , secured to the weight g^3 . By these means the said weight may be lifted by hand and the clutch $e e'$ thus thrown out of gear by the same movement that opens the valve of the cylinder c to admit steam for effecting the pressing of the cloth or other fabric.

To permit the adjustment of the chains and the pressing-plates according to the width of the material to be operated upon, we provide a hand-wheel j , fixed on a shaft j' , which is carried in bearings in brackets attached to the frame of the machine and on which are also fixed the bevel-wheels k , k' , k^2 . These bevel-wheels are geared with other bevel-wheels l , l' , l^2 , fixed on the screw-threaded shafts m , m' , m^2 for adjusting the chains or regulating the distance between the same.

For the sake of brevity we will only describe

the construction acted upon by one of the shafts, as m^2 , it being understood that the others are similar.

The shaft m^2 is free to rotate when the shaft j' is operated, but is held from endwise movement. It is screwed into a cross-bar m^3 , Fig. 3^a, the ends of which are fitted upon the hubs of the chain-wheels C , and are secured thereon by means of collars C^2 . The said chain-wheels are keyed upon the shafts f^{11} , f^{12} , so that they will rotate therewith, but they are free to slide thereon, so that they may be adjusted by turning the shaft m^2 in one or the other direction.

The shaft j' has fixed thereon a worm-wheel n , which gears with another worm-wheel n' , whose axis is at an angle to that of the worm-wheel n . The worm-wheel n' is screw-threaded internally and is fitted upon a screw-threaded shaft o . The worm-wheel n' is free to rotate upon or about its axis; but endwise movement thereof is prevented by the two arms or prongs of a forked bracket n^2 . Therefore when the shaft j' is turned in either direction a corresponding longitudinal movement will be imparted to the shaft o by the worm-wheel or nut n' . The screw-threaded shaft o is secured to the adjustable portions p , p' , p^2 , p^3 of the pressing-plates, the other portions p^* , p'^* , p^{2*} , p^{3*} of which are secured to the steam-chambers q , hereinafter described. Both the adjustable and stationary portions of the pressing-plates are of substantially the shape of a right-angled triangle with the hypotenuse of the one abutting the hypotenuse of the other. Therefore when the shaft j' is rotated the portions p , p' , p^2 , p^3 of the pressing-plates will be moved diagonally in one direction or the other, according to the direction of rotation of the shaft j' , and can be thus adjusted to increase or diminish the width of the pressing-plates.

By referring to Fig. 7 it will be seen that the endless chains for carrying the cloth run in the channels formed between the ends of the pressing-plates and the standards supporting the plate r . In said drawing the numeral 5 indicates the cloth held by its selvage by the chains B , B' , B^2 , B^3 . The action of the chains in pressing against the ends of the movable plates P , P' , P^2 , P^3 is to keep the contiguous edges of the said plates always in contact with the corresponding fixed plates P^* , P'^* , P^{2*} , P^{3*} . The plates P , P' are held together by the filling-blocks P^5 , as shown in Fig. 4, said filling-blocks having bolts or rivets passed through them. So, also, are the plates P^2 , P^3 held together, and as the shaft o engages the plates between the two sets, as shown in Fig. 2, both sets will be moved at the same time.

q , q' are steam-chambers arranged between the pressing-plates for the purpose of heating the same. These chambers are connected with a steam-boiler by means of the pipe q' , as shown in Fig. 4, and a pipe q^2 is provided

for the egress of the steam. r , Figs. 1 and 3, is a fixed plate, which is firmly secured to the frame of the machine.

Each pair of pressing-plates, together with the chamber q between them, rests under normal conditions upon ledges or projections p^4 on the frame of the machine. (See Figs. 7 and 8.) The piston in the cylinder c is then at the bottom of its stroke; but the said plates are free to rise when acted upon by the said piston.

The material to be tented, pressed, and finished is fed into the machine in the wet state in which it comes from the centrifugal machine, and is passed through the machine as follows, viz:

A indicates the feeding end of the machine.

B B' B² B³ indicate the endless tentering-chain.

The material is drawn into the machine by the tentering-chain, and while held by the list or selvage on each side a portion of it is pressed between the plates r and p^4 . After being thus pressed for a few seconds it is again drawn forward by the chains B, and another portion is similarly pressed, and so on. The material then passes with the chains B around the wheels C C' on the shaft f^{12} and is again pressed between the plates p^1 p^{1*} and p^2 p^{2*} , while carried by that part of the chains marked B'. The material is then passed around the chain-wheels G, near the feeding end of the machine, and is carried while on the part of the chains marked B² again between the plates p^1 p^{1*} and p^2 p^{2*} , and is again pressed thereby. It is then passed around the chain-wheels C C' on the shaft f^{11} , and is carried while on that part of the chains marked B³ between the pressing-plates p^3 p^{3*} and the cross head i , which also forms a pressing-plate, and is again pressed. The material is then taken off the chains by the roller-shaft s, and is drawn by the roller-shafts t u v, in the order named, three times through the press between the pressing-plates p^3 p^{3*} and the cross-head i, as shown by dotted lines, Fig. 2. The roller-shaft s has fixed upon its end a bevel-pinion s^2 , gearing with a bevel-pinion s^3 , fixed on the shaft f^8 . By these means rotary motion is imparted to the roller-shaft s. The roller-shaft u is driven by the pinion s^2 through the medium of gearing u^2 on the other side of the machine, as shown in Figs. 1 and 3^b. The roller-shaft v is driven by means of a belt v' , passing around a pulley v^2 , fixed on the said roller-shaft and around a pulley v^3 , fixed on the shaft f^{12} . The said roller-shaft v imparts rotary motion to the roller-shaft t by means of pinions v^4 , only one of which is shown in Fig. 1, the other pinion being directly beneath it. The roller-shaft v is shown as made larger in diameter than the shafts s, t, and u, so as to obtain a greater surface-contact for better drawing off the cloth. Between the plates p^3 p^{3*} and the plate i the material is pressed between highly-glazed pa-

per, or between metal plates or other suitable material, to finish and set it.

Instead of directing a current or blast of hot air upon the surface of the material in the manner ordinarily practiced, we provide means whereby heated air can be passed between the folds of the cloth or other material while it is in the machine. For this purpose we prefer to employ the perforated pipes D, from which the heated air will be ejected in a series of jets. These jets of air drive out the moist heated air and steam, that usually collect between the folds of the material, and also give a softness to the said material, as well as drying the same. To heat the air for this purpose, we prefer to utilize the exhaust-steam from the cylinder c, and we usually effect this by conducting the said exhaust-steam through a receiver provided with tubes or passages through which the air to be heated is forced. This apparatus is shown in detail in Figs. 9 and 10, and comprises two chambers or casings G', located beneath the machine, as shown in Figs. 1 and 2, and each provided with a central pipe or tube H'. The two pipes or tubes H' are connected by the bent pipe I. The exhaust-steam from the cylinder is admitted into the pipes H' through the inlet-pipe J, which is connected with the exhaust-pipe c' of the cylinder c, and the said steam escapes from the said pipes H' through the outlet-pipe K. The space between each pipe H' and the walls of the corresponding chamber G' is divided by partitions L into a series of passages M. The two chambers G' are connected by a pipe N. The air to be heated is forced by means of a fan or blower (not shown in the drawings) into one of the chambers G' through the pipe O and flows through the passages M therein, then through the pipe N into the other chamber G', and through the passages M in this chamber, and leaves the said chamber by the pipe P. This air is heated by contact with the outer surfaces of the pipes H' and with the surfaces of the partitions L, which are formed integrally with the said pipes. After being thus heated the air is forced through pipes Q connecting the pipe P with the perforated pipes D, and escapes between the folds of the cloth or other material being operated upon.

The operation of the press is as follows—that is to say: When the press is in the position shown, the piston in the steam-cylinder c is at rest and the press open, and, as shown in Fig. 3, the tappet or bracket h is in its lowest position, so that the clutch is held in gear by the weight g³ acting upon the lever g. The chains are therefore drawing a portion of the cloth or other material being operated upon into position between the pressing-plates. The driving-pulley a and the gearing connected therewith are arranged to operate relatively to the drawing-in mechanism in such a manner that after each pressing operation is completed the material is passed through the machine a distance of, say, from

eighteen inches to thirty-six inches, but never greater than the width of the pressing-plates. The cam *b*, acting upon the lever *d*, admits steam into the cylinder *c*, the cross-head, table or plate *i* rises, the tappet or bracket *h* throws the clutch out of gear by means of the lever *g* and stops the drawing-in mechanism until the pressing is performed, then the cross-head *i* descends, when the tappet *h* leaves the incline *g*², and the weight *g*³ again puts the clutch in gear for the purpose of bringing a fresh portion of the cloth into position to be pressed.

The stopping and starting of the machine are effected as follows—that is to say: If the attendant, who stands at the feeding end thereof, desires to stop the machine, he moves the lever or arm *E* so as to shift the strap or belt onto the loose pulley *a*³ by means of the fork *E'*. The lever *E* at the same time acts through the rock-shaft *e*², arm *E*², and rod *E*³ upon the lever *F*, and thus lifts the weight *g*³, thereby releasing the lever *g* so that the spring *g*⁷ throws the clutch out of gear, and the drawing-in mechanism comes to rest.

It has been customary heretofore to employ hydraulic pressure in machines of the class above described, and the pressure employed has generally been very considerable, sometimes amounting to two hundred and fifty tons. We have ascertained that quite as good or better results can be obtained by our improvements by employing a slight pressure. We therefore use a steam cylinder and piston instead of hydraulic machinery.

We claim—

1. The combination, with an endless chain for holding and moving the cloth by the lists or selvages, and tentering the same, of a series of vertically-movable heated plates, one above the other, placed in the line of travel of the cloth, and a steam cylinder, piston, and cross-head beneath said plates, and adapted to force them together, whereby the cloth while being tentered will be pressed and finished between the plates, substantially as described.

2. The combination of the cloth-stretching devices, means for adjusting the same, expandable and contractible pressing-plates, and means whereby they will be expanded or contracted simultaneously with the adjustment of the cloth-stretching devices, substantially as set forth.

3. The combination, with the steam pressing-cylinder *c*, provided with an admission-valve, a cam, a power-shaft connected with said cam for operating the same, a lever connecting the said cam with the admission-valve, the pulleys *a* *a*³, the piston-rod *c*', the cross-head *i*, the pressing-plates, the chains, and the screw-threaded shafts *m* *m'* *m*², for separating the chains, of the rock-shaft *e*², lever or arm *E*, fork *E'*, arm *E*², rod *E*³, lever *F*, weight *g*³, lever *g*, chain *g*⁴, connecting said weight and lever, spring *g*⁷, friction-clutch *e*', and suitable gearing connecting said clutch with the moving and tentering chains, all substantially as set forth, for starting and stopping the cam which operates the valve for the admission of steam to the said cylinder, and simultaneously stopping and starting the said cloth-stretching mechanism.

4. The combination, with the cloth-stretching devices, the pressing-plates, the cross-head *i*, the piston-rod *c*', and the steam-cylinder for operating the same, of the perforated pipes *D*, for supplying jets of heated air between the folds of the cloth, a heater, substantially such as described, for heating the air fed to said pipes by passing it in contact with surfaces heated by the exhaust-steam from said cylinder, and pipes for conveying the exhaust-steam from the cylinder to the heater and the heated air from the heater to the pipe *D*, substantially as set forth.

In testimony whereof we have hereunto signed our names in the presence of two subscribing witnesses.
